(57) **CLAIM**

The ornamental design for a fruit picker, as shown and described.

DESCRIPTION

FIG. 1 a perspective view of a fruit picker,

FIG. 2 is a front view of a fruit picker,

FIG. 3 is a right side view of a fruit picker, and,

FIG. 4 is a left side view of a fruit picker.

The broken lines depict portions of the fruit picker that form no part of the claimed design.
